UNITED STATES PATENT OFFICE.

CLEMENT C. CLAWSON, OF NEWARK, NEW JERSEY.

DESIGN FOR A CASE FOR COIN-RECEIVERS.

SPECIFICATION forming part of Design No. 23,155, dated March 27, 1894.

Application filed October 17, 1893. Serial No. 488,429. Term of patent 7 years.

To all whom it may concern:

Be it known that I, CLEMENT C. CLAWSON, a citizen of the United States, residing at Newark, in the county of Essex and State of New Jersey, have invented and produced a new and original Design for Cases of Coin-
receivers; and I do hereby declare the following to be a full, clear, and exact description of the same, reference being had to the accompanying drawings, forming a part thereof.

Figure I is a perspective view of a case embodying the design. Fig. II is a front elevation of the same; and Fig. III is a vertical section in a plane at right angles to the plane of Fig. II.

The leading feature of the design is the inwardly bent front 2 of the inspection chamber A above the box B, the upper and lower parts of the front making a re-entrant angle with each other as shown.

At 3 is a strip to conceal the joint between

the two parts of front 2 where they meet at the apex of the angle. The front 2 and back 4 of chamber A are set between prolongations 5 of the corresponding faces of the box B, 25 which is of greater horizontal depth (i.e., depth as measured from front to back) than the chamber A and has shelf like top portions 6 at the base of and exterior to the chamber A. The chamber A communicates with the box B at 30 the bottom. A top 7 closes the upper end of the chamber A, and there are slots for introducing the coins in said top.

I claim—

The design for a glazed case substantially 35 as herein shown and described.

In testimony whereof I affix my signature in presence of two witnesses.

CLEMENT C. CLAWSON.

Witnesses:

PHILIP W. CROSS,
DENIS D. MULCAHY.
